UNITED STATES PATENT OFFICE.

FRIEDRICH ANINGER, OF MARKT TRIEBENDORF, CZECHOSLOVAKIA.

SHUTTLE-CHANGING DEVICE FOR LOOMS.

Application filed December 22, 1923, Serial No. 682,263, and in Germany October 29, 1923.

This invention relates to shuttle changing devices for looms, and in particular to fly shuttle interchanging mechanism for power looms operating with a movable front wall. Hitherto it has been customary with all known arrangements of this kind to move the front wall by means of a rigid guide in the manner of a gate arrangement or a link motion. The motion of the front wall is effected by means of a special power medium, such as a counter-weight or a spring. Such shuttle arrangements, however, did not enter into general use on account of their many defects and shortcomings, the main difficulties encountered being the wide space between the shuttle magazine and the shuttle box, the wide structure necessitated thereby, the low working speed, the unreliability of the changing gear, and, last, not least, want of economy involved in its use. All these shortcomings can be traced back to the fact that the interchangeable fly shuttle arrangements proposed hitherto are arranged to run in a rigid guide and that the interchange of shuttles is not positively effected by means of a driving shaft or steering gear.

These objections are removed by a device embodying my present invention which comprises means whereby:

- 30 1. The front wall is swung out by motion bars;
2. The path of the front wall is determined by a pair of elements;
3. The movement of the front wall is directly effected and carried out by means of a driving shaft;
- 35 4. A shifting of the front wall accompanied by the rocking of the same is effected.

Two embodiments of this invention are given, by way of example, in the accompanying drawings, wherein:

- Fig. 1 represents a side elevation of a portion of a power loom embodying my invention;
- 45 Figs. 2, 3, 4 and 5 represent four succeeding positions of the parts.

Fig. 6 represents a modified form of apparatus embodying my invention in sectional elevation.

- 50 Fig. 1 shows the frame of the loom with the sword 3 swinging back and forth around pivot 2. From the sword 3 the cloth beam 5 is stretched by the wheel 4. Over the breast beam, which is situated above the cloth beam, 55 the shuttle magazine 6 is provided, in which the full shuttles are placed. The swords 3

carry the lay 7, which is divided into a throw-off binder 8 and a work-box 9. According to the boxes placed into the race board, the shuttle is either caught and thrown out or it is flung back across the loom by the picker and the arm 10 in a manner well understood, and which need not be further described here.

In order to cast out the empty shuttle and replace same by a full one, a motion bar appliance is provided on the lay 7. This consists of a three-armed lever 11, 12, 13 and the single-armed lever 15, carrying the movable front wall 14 of the work or shuttle box 9.

The three-armed lever 11, 12, 13 turns round a rigid steering shaft 16 rigidly attached to the lay 7, while the single-armed lever 15 swings about the end pivot 17 of the lever 13. The bottom side of the lever 15 is provided with an inclined plane or wiper 18 arranged to slide over a friction roller or pulley 19 journaled at the lower end of the lay, the wiper 18 being constantly pressed downwards and against the friction roller or pulley 19 by a spring 20. Another spring 21 attached to the arm 11 of the lever 11, 12 retains the motion bars in the position shown in Fig. 1 so that the front wall 14 is continually pressed against the lay 7, while the work-box is closed. At the other end of the lever 11, 12 a notch or shoulder 22 is provided which is arranged to be engaged by a latch or stop arm 23. The latch or stop arm 23, pivoted at the point 24 on frame 1, is kept in elevated position by a spring 25 so that normally it cannot come into contact with the notch or shoulder 22.

From the latch 23 a belt or cord 26 secured to the same runs over a pulley 27 to a twin-armed lever 28 fulcrumed at point 29 on the breast beam. The end or nose 30 of lever 28 is acted upon by a trip lever 31, and thereby retained in the inclined position indicated in Fig. 1.

The device operates as follows:

Assuming that the bobbin is empty or the thread of the weft torn, the upper nose 30 of the lever 28, held by the trip lever 31 and thereby caused to incline with respect to the lay, is now released and allowed to swing to the right, whereby, through the transmission of this motion by the belt or cord 26, the arm 23 is pulled down. As soon as the lay swings backward (Fig. 2) the notch or shoulder 22 strikes against the latch 23, the

result being a turning of the three-armed lever 11, 12, 13 and thereby of the steering shaft 16.

At the same time the shuttle box 8 is opened in the usual manner by the extension of the lever 13 (Fig. 3), whereby the empty shuttle is caught. By the turning of the three-armed lever, the pivot 17 of the lever 13 moves towards the breast beam, and as the inclined plane 18 travels over the friction roller 19, opens the binder 8 simultaneously with the putting of the work-box into the race board. The opening of the work-box is effected by the swinging out of the front wall 14. The path of the front wall is dependent upon the form of the inclined plane or wiper 18 of the lever 15.

At the end of the motion the pulley or friction roller 19 springs into position behind the shoulder of the wiper or inclined plane 18 and blocks the bars. As the lay now rocks in the reverse direction towards the breast beam, the front wall 14 now locked in position moves underneath the shuttle magazine 6, as indicated in Fig. 4.

As the lay continues this rocking movement, a stop 32, attached to the frame or other fixed part, strikes an extension 33 of the lever 16 and causes the release of the motion bars, and at the same time the return of the roller 19 into contact with the inclined plane 18, thereby causing the front wall to rise behind the shuttle magazine 6. The spring 21 attached to lever 11 can now operate freely to turn the motion bars back into their original position (Fig. 5), at the same time taking a full shuttle from the magazine and placing it into the shuttlebox.

In Fig. 6 is represented a modified arrangement also embodying my invention.

The shuttle arrangement also comprises two shuttle boxes 34 and 35 which are adapted to be moved on the lay 36 transversely to the race board. The box 35 is the throw-box for casting out the empty shuttle. It has a front and rear wall 37, 38. To the lay 36 two guiding pins are fitted with movable slides 40 which are in fixed connection with the rear wall of the box 34. The sword is attached to the pivoted levers 41 which are provided with slots 42, a pin 43 fixed to slide 40 engaging said slots, as shown. The levers 41 are hinged to the levers 44 at their lower ends, which levers carry the front wall 37 of the work-box 35. A spring 45 yieldingly holds the lever 44 against a stop 46.

The levers 41 and 44, hinged to each other, are arranged to swing about their mutual pivot 47 in such manner that, after completion of each motion of the lever 41 to the front, the distance between the walls 37, 38 is only slightly greater than necessary to receive the shuttles.

In order to give full play to the wall 37 in respect to its position in front of the new full shuttle at the bottom of the magazine 48, a pivoted inclined plane or cam 49 is provided. A spring 50 yieldingly draws the cam 49 upward to clear the pin 53. This upward movement is limited by a pin 52 extending from the sword 3 into engagement with a slot 51 in cam 49. The lever 44 has extending from it a guide pin 53 which moves over the bottom surface of cam 49 as the lever 44 advances to the position for exchanging the fly shuttles. The lever 44 now swings on the pivot 54, and by the pin 53 moving over cam 49 is coincidentally drawn downward and passes underneath the shuttle magazine, whereupon, as the pin 53 leaves the cam 49, it is drawn upward by the spring 45. When the lever 44 strikes against the stop 46 it takes its position before the new full fly shuttle in magazine 48, as indicated in dotted lines at the right of Fig. 6. As the work-box slides back into its normal initial position to introduce a new fly shuttle onto the race board, the pin 53 now travels over the upper surface of the inclined plane or cam 49, which is thereby moved downwards against the yielding pressure of spring 50, the pin 53 being thus returned to its initial position, so that, with the next oscillation, the pin will again travel over the bottom surface of the inclined plane or cam 49, whereby the former operation is repeated.

What I claim and desire to secure by Letters Patent is:

1. In a shuttle-changing mechanism, a lay provided with a shuttle-box comprising a movable front wall, and means for rocking the lay, in combination with means for imparting to said front wall a rocking movement away from and toward the shuttle-box and a simultaneous respectively downward and upward shifting movement.

2. In a shuttle-changing machine, a lay provided with a shuttle-box comprising a rear fixed wall on the lay, and a movable front wall, in combination with a steering shaft mounted on the lay, a depending lever pivoted on the steering shaft, a second lever connected to the first lever and bearing the said front wall, and means for rocking the first lever on the steering shaft and rocking the second lever on the first lever downward at the beginning of the forward stroke of the first lever and upward at the end of the said forward stroke and the beginning of the return stroke of said first lever.

3. In a shuttle-changing mechanism, a lay provided with a shuttle-box comprising a movable front wall, in combination with a steering shaft, a lever pivoted on said steering shaft and means for rocking said lever on the steering shaft, a second lever pivoted on the first lever and having said front wall

mounted thereon, an extension on the second lever and a fixed stop in the path of the extension and arranged to cause said second lever to rock upwardly and the front wall to rise on the first lever as it reaches the end of its stroke.

4. In a shuttle-changing mechanism, a lay and oscillatory swords carrying same, and a shuttle box comprising a movable front wall thereon, in combination with a rocking lever pivoted on the swords, and a second lever pivoted to one arm of the first lever and carrying the said front wall and means arranged on a fixed part of the mechanism 15 and the second lever, respectively, to cause an oscillation of the second lever on its pivot, whereby the front wall is caused to rise at the rearward stroke of the swords and to successively pass forward and descend at the 20 beginning of the return stroke.

5. In a shuttle-changing mechanism, lay-carrying reciprocating swords and a shuttle box comprising a movable front wall on the lay, in combination with a lever adapted to 25 rock on a pivot on the swords and a second lever pivoted to the first lever, a contact extension on the second lever and a stop arranged on a fixed part of the mechanism in the path of the contact extension substantially at the end of the rearward stroke of the 30 swords.

6. In a shuttle-changing mechanism, lay-carrying oscillatory swords and a shuttle box comprising a movable front wall arranged on 35 the lay, in combination with a lever fulcrumed on the sword and yieldingly urged in one direction, an extension on said lever and a stop in the path of the extension arranged to cause said lever to rock in the

opposite direction, a second lever carrying 10 the front wall and fulcrumed on the first lever, a cam or wiper on the second lever and a part on the lay over which the cam or wiper is arranged to travel, an extension on 45 the second lever and a contact arranged on a fixed part of the mechanism in the path of the extension substantially at the end of the rearward stroke of the swords.

7. In a shuttle-changing mechanism, a shuttle magazine, lay-carrying swords arranged to rock toward and past and back from the magazine and a shuttle box on the lay, in combination with a lever fulcrumed on 50 the swords, a second lever fulcrumed on the first lever and carrying the front wall of 55 the shuttle box, and means for oscillating the second lever with respect to the first during the oscillation of the sword so as to cause the front wall to pass under, upward in front of and forward and past the lower 60 part of the magazine and toward the work box as the swords rock back and forth.

8. In a shuttle-changing mechanism, a shuttle magazine, lay-carrying swords arranged to rock back and forth with respect 65 to the magazine, and a shuttle box on the lay, in combination with a lever fulcrumed on the swords and provided with an extension, a stop arranged in the path of the 70 first lever, a second lever fulcrumed to the 75 first lever, a cam or wiper on the second lever and a part on the lay over which the cam or wiper is arranged to travel, an extension on the fulcrum of the second lever and a stop on a fixed part of the mechanism and arranged in the path of said extension.

In testimony whereof I affix my signature.
FRIEDRICH ANINGER.
